UNITED STATES PATENT OFFICE

154,903

DESIGN FOR A REVERSIBLE SOAP DISH

James R. Caldwell, Wooster, Ohio, assignor to
The Wooster Rubber Company, Wooster, Ohio

Application March 29, 1948, Serial No. 145,418

Term of patent 14 years

(Cl. D4—3)

To all whom it may concern:

Be it known that I, James R. Caldwell, a citizen of the United States, residing at Wooster, in the county of Wayne and State of Ohio, have invented a new, original, and ornamental Design for Reversible Soap Dish, of which the following is a specification, reference being had to the accompanying drawing, forming part thereof, wherein:

Figure 1 is a perspective view of a reversible soap dish embodying my new design, having the drain receptacle portion uppermost as when in use.

Figure 2 is a view similar to Figure 1, illustrating the article as when turned up-side-down in reference to its position as illustrated in Figure 1.

Figure 3 is a transverse sectional view of the article, the view being taken transversely through the central portion of the structure as shown in

Figure 1 and the section being lined to represent rubber.

I claim:

The ornamental design for a reversible soap dish, substantially as shown.

JAMES R. CALDWELL.
